UNITED STATES PATENT OFFICE

FRED J. BALK AND JOSEPH J. BALK, OF UNION CITY, NEW JERSEY

CLOSURE FASTENER

Application filed June 18, 1929. Serial No. 371,764.

This invention relates to new and useful improvements in closure fasteners and more particularly to a novel window securing device.

5 The principal object of this invention is to provide a window fastener which may be adjusted to permit a partial opening of the window sashes for the purpose of ventilation without allowing unauthorized entry. 10 Another salient object of the invention is to provide a window fastener for securing a window in closed position, in partially opened position, or which may be adjusted to permit the full opening of the window, 15 as the occasion may require.

Other objects consist in the provision of a window fastener which will be comparatively easy to install, positive-acting in operation, and which because of its sturdy construction, will be exceedingly durable.

In the drawing:—

Figure 1 represents a front elevation of the novel fastener, associated with the sashes of a window and in position for securing the 25 said sashes in window closed position.

Fig. 2 represents a vertical sectional view through a conventional window structure taken substantially on the line 2—2 of Fig. 1 and showing in edge elevation, the window 30 fastener in window secured position.

Fig. 3 represents a horizontal sectional view taken through the device approximately on the line 3—3 of Fig. 1, but showing the swingable arm maintained against the stationary bar so as to permit the free movement of the sashes without interference by the fastening device.

Fig. 4 represents a perspective view of the structure carried by the lower sash.

40 Fig. 5 represents a side elevation of the swingable arm.

Fig. 6 represents an edge elevation of the swingable arm.

Fig. 7 represents a front elevation of the 45 stationary bar to which the swingable arm is connected.

Fig. 8 represents an edge elevation of the stationary bar.

50 Fig. 9 represents a fragmentary sectional view disclosing the hinged connection be-

tween the swingable arm and the said stationary bar.

Referring to the drawings wherein like numerals designate like parts, it will be seen that the improved fastener is to be associated with a window construction of the type including the usual rectangular frame 5 in which the upper and lower sashes 6 and 7 are 55 slidable.

The novel fastener includes an elongated 60 bar 8 provided with openings 9 (preferably countersunk), for receiving screws in the attachment of the bar to the upper sash 6. This bar is adapted to be attached to the upper sash at the inner side thereof and adjacent the upper rail of the lower sash 7. The upper end of the bar is provided with a pair of upwardly extending hinge knuckles 10.

An elongated arm 11 substantially longer 70 than the bar 8 is provided at one end with a pair of hinge knuckles 12. A pin 13 is employed for connecting the knuckles of the arm 11 to the knuckles of the bar 8 and a coiled spring 14 with its ends impinging against the 75 bar and arm, is convoluted on the pin 13 in the manner shown in Figs. 1 and 9. The knuckles of the bar 8 are provided with laterally disposed stops 15 against which the arms 11 may abut when disposed upwardly to assume the 80 horizontal plane (see Fig. 2), by the tension of the coiled spring 14.

The end of the arm 11 opposite from the 85 knuckles 12 is provided with a transversely disposed tubular member 16, while a finger 17 is disposed laterally from the intermediacy of the arm 11 and is bent toward the bar 8 in a manner whereby the same may snap over the edge of the said bar to maintain the arm snugly against the bar as 90 in the manner shown in Fig. 3, when it is desired that the fastener be moved out of the path of the sashes, so that the same may be moved freely.

The invention also includes a latch device generally referred to by the numeral 17. This latch device includes a base plate 18 bent at one end to provide a depending flange 19. The intermediacy of the plate is disposed upwardly and formed to provide 95 100

an elongated barrel 20 and a relatively shorter barrel 21 alined with respect to the barrel 20, yet spaced a substantial distance therefrom to permit the interposition of the tubular member 16 of the arm 11.

5 The plate 18 is provided with openings 22 through which screws may be disposed for securing the plate to the upper rail of the lower sash 7, the flange 19 being disposed over the inner side of the said rail in the manner shown in Fig. 2.

A bolt is slidably disposed within the barrel 20 and is engageable within the barrel 21 and at one end. The bolt is provided 15 with a projection extending through a longitudinal slot 24 in the barrel 20 and this projection is equipped with a finger engageable enlargement 25. The slot 24 is provided with an offset 26 for receiving the said projection 20 in maintaining the bolt projecting to a position with its end locked within the short barrel 21 and obviously through the tubular member 16 of the arm 11, when said member is interposed between the said barrels 20 25 and 21. In this manner the sashes may be secured against movement within the frame 5 of the window.

In order to permit a partial opening of the sashes for the purpose of ventilation, the 30 arm 11 is released from the latch device 17, whereupon it assumes the horizontal position shown in dotted lines in Fig. 2.

The arm 11 will be prevented from moving upwardly beyond this point due to its abutment against the stops 15. The sashes may 35 be then moved to a position where the upper rail of the lower sash 7 will abut the arm 11.

However, when it is desired that the sashes be free to move without interference by the 40 fastening device, the arm 11 is pressed against the bar 8 so that the spring catch 17' will engage over the edge of the said bar 8, whereby it will be maintained in the position shown in Fig. 3.

45 While the foregoing description has been in definite terms, it is to be understood that various changes in the specific shape, size, materials may be resorted to without departing from the spirit and scope of the invention 50 as claimed hereinafter.

Having thus described our invention, what we claim as new is:-

1. A securing device comprising a plate 55 adapted to be secured to one sash, a pivotal arm carried by the said plate, a latch on the other sash, means on the free end of the arm for engagement by the said latch, and spring means for maintaining the arm in a horizontal position after the release thereof from the 60 said latch means.

2. A securing device for sliding sashes, 65 comprising a plate secured to one of the sashes, an arm pivotally connected to the said plate, complementary means between the free end of the arm and the other sash, whereby

the sashes may be maintained against movement, means between the said plate and the arm, whereby the arm may be maintained snugly against the said plate and out of the path of the sash, and a member projecting 70 from the said plate for limiting the upward movement of the said arm.

3. A securing device for sliding sashes comprising a plate secured to one of the said sashes, an arm pivotally connected to the said plate, complementary means between the free end of the arm and the other sash, whereby the sashes may be maintained against movement, means between the said plate and the arm whereby the arm may be swung outwardly to a horizontal position to restrict movement of the sashes in overlapping relation.

4. A securing device for sliding sashes comprising a plate secured to one of the said sashes, an arm pivotally connected to the said plate, complementary means between the free end of the arm and the other sash, whereby the sashes may be maintained against movement, means between the said plate and the arm whereby the arm may be swung outwardly to a horizontal position to restrict movement of the sashes in overlapping relation, and a projection on the said plate for limiting the upward movement of the said arm.

In testimony whereof we affix our signatures.

FRED J. BALK.
